FOOT-CLEANING MAT

Application filed March 17, 1927, Serial No. 176,168, and in the Netherlands June 25, 1926.

This invention relates to foot-cleaning mats, particularly for use in hotels, restaurants, banks, and other large buildings, where a continuous arrival of visitors may generally be expected.

The object of the invention is to provide a foot-cleaning device which operates automatically, that is, which is so formed that the soles of the boots or shoes of every visitor 10 who in entering treads upon the mat are automatically and thoroughly cleaned, whether the entering person stands still or continues moving.

Foot-cleaning mats are already known 15 with cleaning devices movably arranged between the bars of a grid-like foundation made of wood or iron.

The invention consists herein, that means are provided for setting these cleaning 20 devices in a to and fro movement. Preferably with such an arrangement the drive of the cleaning devices is so chosen that the directions of movement of each two succeeding cleaning devices are opposite to one another. 25 In this manner a complete cleaning of the boots or shoes is ensured.

The oppositely directed to and fro movements of the cleaning devices which take place with very high speed can, according to the 30 invention, be derived from two sets of approximately parallel shafts located on both sides of the grid, which are oscillated back and forth over an equal angle in opposite directions, the arrangement being such that the 35 ends of each two succeeding devices located on the same side are connected by a flexible connection with different shafts of the set corresponding thereto, and the two ends of each cleaning device are in connection with 40 two shafts rotating in the same direction.

In the accompanying drawings a constructional form of the invention is illustrated by way of example, in which—

Fig. 1 is a plan of a part of a foot-cleaning mat according to the invention;

Fig. 2 is a cross-section on the line II—II of Fig. 1;

Fig. 3 is a cross-section on the line III—III of Fig. 1 drawn to a larger scale and looking 50 in the direction of the arrows and Figs. 4 and

5 show diagrammatic views of the oscillating means.

Referring to the drawings, the foot-cleaning mat illustrated herein consists mainly of a grid-like frame 1, of which the grid bars 55 are formed of supporting plates 2 arranged parallel and equidistant from one another, the ends of which are connected to housing 3 extending along two sides of the grid. Between each two supporting plates 2 is located a cleaning device which, in the constructional form illustrated, consists of a brush 4 which on the lower side is fixed upon a band or wire 5 which passes through the inner wall of the housing 3 and is moved in a manner hereinafter more particularly described.

In each housing 3 is disposed a set of two parallel shafts 6, 7, and 8, 9, which by means of spur wheels 10, 11, and 12, 13 are connected with one another. To one of the shafts of each set is communicated, preferably by means of a driving device common to both sets, a rapid oscillating rotary movement through quite a small angle, which rotary movement is transmitted by the spur wheels 70 in the opposite direction to the second shaft of each set. Upon the shafts are mounted chain wheels 14, 15, or 16, 17, in the constructional form shown, in which the chain wheels 75 of the one shaft are displaced relatively to those of the other shaft. Round these chain wheels are passed short chains 18, 19, one end of which is connected with the wire 5 of the appropriate brush while the other ends of the chains remain in connection with one another by a second wire 20. The arrangement is adapted so that the ends of each two succeeding brushes located on the same side 80 co-operate with different shafts of the proper set, in such a manner that the two ends of each brush are connected with two shafts rotating in the same direction. Thus when, in the constructional form shown, the wire 5 of one brush is connected with chains which circulate round the chain wheels 14 and 16, the former on the outer shaft 6 of one set and the latter on the inner shaft 8 of the second set 85 rotating in the same direction, the chains with which the wire 5 of the next brush is

85

100

connected are arranged to circulate round the chain wheels 15 and 17 which are fixed the former upon the inner shaft 7 of the first set and the latter upon the outer shaft 9 of the second set.

5 Fig. 4 shows suitable means for rocking the shaft 9 and thus reciprocating the cleaning devices. In this arrangement the shaft 9 or an extension thereof carries a lever A rigidly secured thereon and the free end of the lever is pivotally connected to one end of a rod B the other end of which is connected to a crank or crank disc C driven by any suitable motor, for example an electric motor, 10 in such a manner that upon the crank C being rotated the lever A is oscillated and the shaft 9 is rocked. This rocking movement is transmitted to the shaft 8 by means of the mutually 15 engaging spur wheels 13 and 12 and the rocking motions of the shafts 9 and 8 are transmitted by the short chains 18, 19, and wires 5 and 20 to the cleaning devices, such as the brushes 4, as shown in Fig. 3.

In the arrangement shown in Fig. 5 the 20 cleaning devices are mounted on two interconnected rocking levers A, A', acted upon the crank C of the motor.

In this manner is obtained a consecutive 25 series of cleaning elements in which the adjacent elements, on the shaft being driven, are moved in a rapid to and fro motion in opposite directions to one another. The common surface of the cleaning elements extends normally somewhat beyond the supporting 30 plates 2; as however the wires 5 are flexible the corresponding elements will yield locally under the pressure of the foot, until the foot is supported upon the upper edge of the supporting plates 2. By the rapidly moving 35 cleaning elements under the foot the sole of the boot is thus thoroughly cleaned without it being necessary for the person to stand still upon the mat. It is clear that instead of the cleaning elements shown and described 40 other cleaning devices can be used, while other changes also can be made in carrying out the invention without exceeding the ambit of the claims.

What we claim is:—

50 1. A foot-cleaning mat comprising a grid foundation having a plurality of parallel spaced bars, movable cleaning elements arranged between the said bars, and means associated with said cleaning elements to direct a reciprocating movement of each two consecutive movable cleaning elements in opposite directions to each other.

55 2. A foot-cleaning mat comprising a grid foundation having a plurality of parallel spaced bars, movable cleaning elements arranged between the said bars, a pair of parallel shafts disposed at each end of said foundation normal to said bars, a plurality of pulleys arranged on said shafts, means for effecting 60 the opposite oscillation of the shafts of each

pair, and flexible connecting means connecting the ends of each movable cleaning element with the pulleys on the two shafts moving in the same direction, said movable cleaning elements being connected to said shafts to effect the movement of adjacent movable cleaning elements in opposite directions.

In testimony whereof, we affix our signatures.

WILLEM JACOB HOOGEWEG.
EMANUEL VAN OVEN.
